UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,847**, dated September 2, 1873; application filed August 9, 1873.
[Term of Patent 3½ years.]

Z.

To all whom it may concern:

Be it known that I, FREDERICK WINK, of the city and county of Philadelphia, State of Pennsylvania, have invented a Design for a Shawl-Pattern, of which the following is a specification:

The main features of my design, which is clearly illustrated by the figure in the accompanying drawing, are the wide and narrow stripes A and B.

The stripe A has a central rib, *a*, ornamented by rows of dots and dashes, as shown, and is otherwise composed of minor parallel plain stripes, bars, or ribs of different widths and shades or colors. The stripe B has at each edge a rib, *b*, ornamented internally by par-

allel rows of dots and dashes and by a peculiar serrated edging.

Irrespective of the colors employed, I claim—

1. The design for the stripe A, as shown and described.
2. The design for the stripe B, as described and represented.
3. The design for the whole pattern, including the stripes A and B.

In testimony whereof I have signed my name to this specification in the presence of two subscribing witnesses.

FRED. WINK.

Witnesses:

CLINTON M. LATOURETTE,
LEWIS T. GODFREY.
